ELECTRIC SWITCH

Filed Dec. 21, 1927

UNITED STATES PATENT OFFICE

HARRY A. DOUGLAS, OF BRONSON, MICHIGAN

ELECTRIC SWITCH

Application filed December 21, 1927. Serial No. 241,641.

My invention relates to electric switches and in accordance with one feature thereof, a contact member is spring pressed into normally permanent engagement with a circuit 5 terminal to constitute an electrical continuation of such terminal, this contact member being movable into and out of engagement with a complementary contact or terminal.

In accordance with another feature of the 10 invention, a fulcrum is provided for such contact member and means are employed for relatively shifting the fulcrum and the place of contacting engagement of the contact member whereby the circuit opening and 15 closing movements of the contact member may be rapidly effected.

The invention will be more fully explained in connection with the accompanying drawing in which Fig. 1 is a vertical sectional view 20 illustrating a form of the invention, showing the switch in a circuit opening adjustment; Fig. 2 is a sectional view on line 2—2 of Fig. 1; Fig. 3 is a plan view showing a mounting panel in section; Fig. 4 is a view similar 25 to Fig. 3 but showing the casing in section and parts broken away; Fig. 5 is a sectional view on line 5—5 of Fig. 1; and Fig. 6 is a view, partially in section and partially in elevation, showing the switch in a circuit 30 closing adjustment.

The switch structure illustrated includes a casing 1 which is fixed upon the inner end of an exteriorly threaded bushing 2 which is held in place by means of nuts 3 and 4 35 screwed thereon and between which the dash board 3 or other mounting is clamped. The casing 1 is of inverted cup shape, the lower end of the casing being closed by a disc 6 of insulation. The circuit wires 7 and 8 are 40 suitably connected with circuit terminals. The circuit terminal with which the wire 7 is connected includes a metallic post 9 passing through the disc 6 and having flanges 10 and 11 upon its ends and between which the disc is tightly received, a binding screw 12 for clamping the wire 7 in place, and the metallic leaf extension 13. Said leaf extension 45 has a cup shaped portion 13' constituting a socket which receives the outer end of the metallic contact plunger 14 whose outer end

is rounded to conform to the shape of said socket whereby said plunger contact may readily be bodily turned. The plunger contact is pressed into engagement with the socket by means of the metallic coiled spring 55 15 which is contained in a metallic spring barrel 16.

The circuit terminal with which the wire 8 is connected includes a metallic post 17 passing through the disc 6 and having flanges 18 and 19 upon its ends and between which the disc is tightly received, and a binding screw 20 for clamping the wire 8 in place. The flange 18 is enlarged to constitute a contact which is positioned to be engageable by the 60 spring barrel 16 when the wires 7 and 8 are to be connected, means being provided for oscillating the spring barrel into and out of engagement with said flange 18. The spring barrel is desirably mounted in a carrier 21 of insulation, this carrier being enlarged at its upper end to receive the lower and rounded edge of a rectangular fulcrum plate 22 whose top edge engages the top of the casing 1 which holds this plate from rotation. The fulcrum is shifted by the stem 23 of a reciprocal handle 24, this stem sliding in the bore of the bushing 2. When the stem is in its innermost position, the fulcrum is 65 upon the right of the place of engagement 70 of the contact plunger 14 with the terminal portion 13 and when the stem is in its outermost position, the fulcrum is upon the left of such place of engagement. The fulcrum and handle stem are desirably assembled by 75 providing the stem with a peripheral annular groove 25 that receives the fulcrum plate, the fulcrum plate, itself, being formed with a slot 26 which receives the handle stem 80 in the zone of the groove 25. This assembly 85 of the handle stem and fulcrum plate permits the handle to be turned without damage and without effecting any circuit change, though it is understood that the invention is not to 90 be limited to a structure in which the circuit changing movements are effected by a reciprocal handle.

Changes may be made without departing 95 from the invention. 100

Having thus described my invention, I claim:

1. In an electric switch, the combination with two circuit terminals; of a contact member which is inclusive of a compressible spring, a plunger contact pressed upon by the spring and having rocking engagement with one of said circuit terminals, and a carrier for said plunger contact and spring; and a reciprocable handle having a fulcrum formation engaged by said carrier and upon which the carrier may turn in response to reciprocation of the handle, the handle being shiftable to bring the fulcrum formation thereon upon one side or the other of the place of engagement of the plunger contact and the circuit terminal upon which the plunger contact may rock, the aforesaid spring maintaining said carrier in engagement with said fulcrum formation in all positions of the handle, whereby the contact member has the final portions of its alternative movements quickly completed, the other circuit terminal being positioned to be engaged by said contact member when this member is in one of its alternative positions.

2. In an electric switch, the combination with a current conducting contact in the form of a spring barrel; of a plunger projecting from said spring barrel; a spring within the spring barrel and pressing outwardly upon the plunger; a member upon which said plunger is pressed by the spring and upon which the plunger is turned, together with the spring barrel, by the spring; a contact complementary to the spring barrel contact and engaged thereby when the latter contact is turned by the spring; and a switch handle operable upon the spring barrel and plunger to cause the same to turn and serving to separate the spring barrel contact from the other.

3. The structure of claim 2 wherein the plunger and the member upon which the plunger turns are current conducting contacts.

In witness whereof, I hereunto subscribe my name.

HARRY A. DOUGLAS.
